IGNITION APPARATUS FOR INTERNAL-COMBUSTION ENGINES.

1,424,056.

Specification of Letters Patent. Patented July 25, 1922.

Application filed July 18, 1918. Serial No. 245,489.

To all whom it may concern:

Be it known that I, NIKLAS WINBLAD, a citizen of the United States, and a resident of Stepney, in the county of Fairfield and 5 State of Connecticut, have invented an Improvement in Ignition Apparatus for Internal-Combustion Engines, of which the following description, in connection with the accompanying drawings, is a specification, 10 like characters on the drawings representing like parts.

This invention relates to ignition apparatus for internal combustion engines, and is more especially concerned with housings for 15 the conducting wires or cables leading to the spark plugs and grounding switch.

My invention will be best understood by reference to the following description, when taken in connection with the accompanying 20 drawings of one specific embodiment thereof, while its scope will be more particularly pointed out in the appended claims.

In the drawings:

Fig. 1 is a plan of a portion of an internal 25 combustion engine equipped with an ignition apparatus embodying my invention;

Fig. 2 is a side elevation of the same;

Fig. 3 is a detail plan on an enlarged 30 scale, showing the cables and cable housing with the upper sections of both outer and inner casings removed;

Fig. 4 is a sectional view on line 4—4 of Fig. 1;

Fig. 5 is a rear end elevation of the cable 35 housing on an enlarged scale;

Fig. 6 is a front end elevation of the same on an enlarged scale; and

Fig. 7 is a sectional view on an enlarged 40 scale on line 7—7 of Fig. 1.

Referring to the drawings, and to the embodiment of my invention which is illustrated therein, I have shown a portion of an internal combustion engine having a plurality of cylinders, which may be of any desired number, but in the present example, I have shown a monobloc motor having six cylinders, designated respectively 10, 11, 12, 13, 14 and 15, all formed as a part of a single casting 16 provided with a usual 45 water jacket 17 having a water space 18 surrounding the several cylinders. This space in the present example is closed by a plate 19, which, as will presently appear, forms a

part of a housing for the ignition cables. This plate may be, and is herein, provided 55 with a passage 20 leading from the water space 18 adjacent the front end of the motor at a point convenient for connection to the usual radiator, not shown. The cylinders may be equipped with any usual or desired 60 spark plugs 21, 22, 23, 24, 25 and 26, to which current may be supplied by any usual or desired magneto or generator having a distributor 27, conventionally represented in Fig. 1. From this distributor, usual cables 28, 29, 65 30, 31, 32 and 33, lead to the several spark plugs. The electric apparatus may also include cables 34, 35, 36 and 37, connecting other instruments of the system, as for example, a usual grounding switch, horn and other accessories. As a means to hold the several cables in their proper positions, and prevent injury thereto by protecting them from water, oil, dust and mechanical injuries, I have provided a novel housing which 70 I shall now describe.

In the housing selected for exemplification, I have provided an outer casing made up of two separable sections, one of them preferably formed as a part of the plate 19, 80 and the other as a cover 38. These sections, together, form a chamber 39, providing a convenient enclosure for an inner casing comprising separable sections 40 and 41, in which the various cables may be enclosed 85 in any appropriate manner. Preferably, the cables enter the housing in a group at one side of the latter, through a bushing 42 preferably formed of insulating material, and preferably provided with outer and inner 90 flanges 43 and 44, interlocked with the lateral wall of the outer casing, as best shown in Fig. 3. Preferably, this bushing is longitudinally divided, as best shown in Fig. 2, thereby to facilitate the introduction of the 95 cables into suitable openings of the proper size to receive and hold the cables firmly. The cables 28, 29, 30, 31, 32 and 33, preferably emerge from the housing through individual bushings 45, 46, 47, 48, 49 and 50, 100 respectively, preferably formed of suitable insulating material. If desired, these bushings also may be divided in a horizontal plane to facilitate the introduction and removal of the cables, and preferably they are 105 flanged and interlocked with the lateral wall

of the casing in a manner similar to the bushing 42. So, also, the cables 34, 35, 36 and 37, extend through a bushing 51, which is preferably formed of suitable insulating material and flanged so as to interlock with the outer casing as clearly shown at the left-hand end of Fig. 4. This bushing, like the others, is preferably divided in a horizontal plane, but differs therefrom in the provision 5 of a separator 52, also preferably formed of insulating material interposed between the upper cables 34 and 35 and the lower cables 36 and 37 as best shown in Fig. 5. This separator, like the bushing itself, is 10 preferably interlocked with the outer casing, as best shown in Fig. 3.

Preferably, the upper and lower parts 38 and 19 of the outer casing are separated from each other by a space 53, sufficient to 15 permit these parts to be forced toward each other, thereby to clamp the various bushings in place. Any suitable means may be provided to furnish the desired clamping action, but in the present example, I have 20 shown studs 54 and 55, screwed into the cylinders 11 and 14, respectively, and extending through the inner and outer casings, as 25 best shown in Fig. 4. Nuts 56 and 57, threaded onto said studs, serve as a means 30 for securing the plate 19 in place to close the water space 18. Nuts 58 and 59, threaded onto the studs 54 and 55, respectively, serve 35 to draw the upper section 38 of the casing in a downward direction toward the lower 40 section, thereby to clamp the bushings therebetween. Similar studs 60, 61, 62, and 63, though shorter than the studs 54 and 55, are 45 threaded into the cylinders 10, 12, 13 and 15, respectively, and provided with nuts 64, 65, 66 and 67, to assist the nuts 56 and 57 in securing 50 the plate 19 in place. It is evident that, by removing the nuts 58 and 59, the outer casing may be opened for the purpose of gaining access to the cables, but that removal of the entire casing from the cylinders can be accomplished only by the removal of the nuts 56, 57, 64, 65, 66 and 67.

Referring again to the inner casing parts 40 and 41, the latter are preferably grooved or channeled, as shown in Figs. 4 and 7, to receive and snugly hold the several cables and to prevent any interference between them. Preferably, the cables 30 and 31, which are in the upper part 41, are spaced 55 apart from the cables 32 and 33, which are in the lower part, by a separator 68, best shown in Figs. 3 and 7. Similarly, the cables 34 and 35 are separated by a similar separator 69, also shown in Figs. 3 and 7, 60 thus preventing any possible interference or short circuiting. Preferably, these separators are made of appropriate insulating material.

The inner casing parts 40 and 41 may be 65 secured to each other and to the outer casing

by clamping screws 70 and 71, best shown in Fig. 4, extending through both parts and threaded into lugs 72 and 73 formed on the plate 19. Thus it is evident that when the parts 40 and 41 are secured together, the 70 cables are firmly held therein, and cannot be removed or become accidentally displaced, without first removing the screws 70 and 71.

In order to ventilate the housing, I have 75 herein provided the lateral walls of the plate 19 with suitable apertures 74, 75, 76, 77, 78, 79 and 80, which serve to admit cool air to the chamber 39, and permit the escape of warm air therefrom. The apertures 74 and 80 are formed in the front and rear ends respectively, of the casing, while the remaining apertures are provided in the two sides, thus affording free passage of the air on all sides.

While I have herein shown and described 85 one specific embodiment of my invention for illustrative purposes, and have disclosed and discussed in detail the construction and arrangement incidental to one specific application thereof, it is to be understood that the invention is limited neither to the mere details or relative arrangement of parts, nor to its specific embodiment herein shown, but 90 that extensive deviations from the illustrated form or embodiment of the invention 95 may be made, without departing from the principles thereof.

Having thus described one form of my invention, what I claim and desire by Letters 100 Patent to secure is:

1. In an ignition apparatus for internal combustion engines, the combination of a spark-plug, a cable leading to said spark-plug, and a divided housing presenting a 105 longitudinal chamber formed partly within each division and enclosing said cable, the latter being received partly in each division.

2. In an ignition apparatus for internal combustion engines, the combination of a 110 plurality of spark-plugs, a plurality of cables leading to said spark-plugs, respectively, and a housing enclosing said cables and comprising two separable parts presenting a chamber partly in each for said 115 cables, each cable having a portion of its length received partly in each of said separable parts.

3. In an ignition apparatus for internal combustion engines, the combination of a 120 plurality of spark-plugs, a plurality of cables leading to said spark-plugs, respectively, and a housing enclosing said cables and comprising a divided outer casing presenting a chamber formed partly within each division and an inner cable support.

4. In an ignition apparatus for internal combustion engines, the combination of a 125 plurality of spark-plugs, a plurality of cables leading to said spark-plugs, respec- 130

tively, and a housing enclosing said cables and comprising a divided outer casing and a divided inner casing.

5. In an ignition apparatus for internal combustion engines, the combination of a plurality of spark-plugs, a plurality of cables leading to said spark-plugs, respectively, and a housing enclosing said cables and comprising a divided outer casing and 10 a divided inner casing provided with cable receiving channels.

6. The combination of an internal combustion engine having a plurality of cylinders provided with a head having a two-part 15 chamber and entrances therein, a plurality of spark-plugs for said cylinders, respectively, and a plurality of cables disposed in said chamber and leading through said entrances to said spark-plugs, respectively.

20 7. The combination of an internal combustion engine having a plurality of cylinders provided with a head having a chamber therein, a plurality of spark-plugs for said cylinders, respectively, and a plurality of 25 cables disposed in said chamber and leading to said spark-plugs, respectively, said head having means providing for the cooling of said chamber by the admission of cool air thereto and the escape of warm air therefrom.

30 8. The combination of an internal combustion engine having a plurality of cylinders provided with a head having a chamber therein, a plurality of spark-plugs for said 35 cylinders, respectively, and a plurality of cables disposed in said chamber and leading to said spark-plugs, respectively, one of said parts being apertured to provide for the cooling of said chamber by the admission of 40 cool air thereto and the escape of warm air therefrom.

9. The combination of an internal combustion engine having a plurality of cylinders provided with a water-jacket space, a 45 plurality of spark-plugs for said cylinders, respectively, a plurality of cables leading to said spark-plugs, respectively, and a cable-housing comprising a casing having separable sections, having a chamber formed 50 partly in each, one section constituting a closure for said water-jacket space, said cables being housed within said chamber.

10. The combination of an internal combustion engine having a plurality of cylinders provided with a water-jacket space, a 55 plurality of spark-plugs for said cylinders, respectively, a plurality of cables leading to said spark-plugs, respectively, a cable-housing comprising a casing having separable 60 sections, one constituting a closure for said water-jacket space, and common means to secure said separable sections to each other and to said cylinders.

11. The combination of an internal com- 65 bustion engine having a plurality of cylin-

ders provided with a water-jacket space, a plurality of spark-plugs for said cylinders, respectively, a plurality of cables leading to said spark-plugs, respectively, a cable-housing comprising a casing having separable 70 sections, one constituting a closure for said water-jacket space, means to secure said separable sections to each other and to said cylinders, and other means to secure one of said sections to said cylinders. 75

12. The combination of an internal combustion engine having a plurality of cylinders provided with a water-jacket space, a plurality of spark-plugs for said cylinders, respectively, a plurality of cables leading to 80 said spark-plugs, respectively, a cable-housing comprising a casing having separable sections, one constituting a closure for said water-jacket space, fastening means extending from said cylinders through one of said 85 separable sections to secure the same thereto, and fastening means extending from said cylinders through both sections to secure the same to each other and to said cylinders.

13. In an ignition apparatus for internal 90 combustion engines, the combination of a plurality of spark-plugs, a plurality of cables leading thereto, a longitudinally divided casing through which said cables extend, and bushings through which said cables 95 lead into said casing, said bushings being received between the divisible parts of said casing.

14. In an ignition apparatus for internal combustion engines, the combination of a 100 plurality of spark-plugs, a plurality of cables leading thereto, a longitudinally divided casing through which said cables extend, bushings through which said cables lead into said casing, and means to cause said 105 casing to clamp said bushings in place.

15. In an ignition apparatus for internal combustion engines, the combination of a 110 plurality of spark-plugs, a plurality of cables leading thereto, a longitudinally divided casing through which said cables extend, and divided bushings through which said cables lead into said casing.

16. In an ignition apparatus for internal combustion engines, the combination of a 115 plurality of spark-plugs, a plurality of cables leading thereto, a divided enclosure for said cables, and longitudinally disposed separating means distinct from said enclosure and interposed between said cables. 120

17. In an ignition apparatus for internal combustion engines, the combination of a plurality of spark-plugs, a plurality of cables leading thereto, a divided enclosure for said cables, and one or more longitudinal 125 separators interposed between the parts of said enclosure and separating said cables.

18. In an ignition apparatus for internal combustion engines, the combination of a plurality of spark-plugs, a plurality of ca- 130

bles leading to said spark-plugs, and a longitudinally divided housing having a cable-receiving chamber and one or more entrances intersected by the line or plane of division.

- 5 19. In an ignition apparatus for internal combustion engines, the combination of a plurality of spark-plugs, a plurality of cables leading to said spark-plugs, and a housing comprising two parts enclosing said cables and providing a cable-receiving chamber and one or more entrances formed partly in each.
- 10 20. In an ignition apparatus for internal

combustion engines, the combination of a plurality of spark-plugs, a plurality of cables leading to said spark-plugs, and a housing comprising two separable parts forming together a chamber and one or more entrances thereto, separation of said parts exposing a continuous open channel having 20 two ends presenting entrances intermediate opposite sides of said housing and permitting said cables to be simply laid in place.

In testimony whereof, I have signed my name to this specification.

NIKLAS WINBLAD.

Certificate of Correction.

It is hereby certified that in Letters Patent No. 1,424,056, granted July 25, 1922, upon the application of Niklas Winblad, of Stepney, Connecticut, for an improvement in "Ignition Apparatus for Internal-Combustion Engines," errors appear in the printed specification requiring correction as follows: Page 2, line 105, claim 1, before the word "divided" insert the word *longitudinally*, and line 106, strike out the word "longitudinal"; page 3, line 95, claim 13, for the misspelled word "busings" read *bushings*; and that the said Letters Patent should be read with these corrections therein that the same may conform to the record of the case in the Patent Office.

Signed and sealed this 19th day of September, A. D., 1922.

[SEAL.]

WM. A. KINNAN,

Acting Commissioner of Patents.
